TABLE LAMP

Charles W. Clemens, Nashville, Tenn., assignor to Aladdin Industries, Incorporated, Nashville, Tenn., a corporation of Illinois

Application March 8, 1955, Serial No. 34,943

Term of patent 7 years

(Cl. D48—20)

FIG. 1.

The dominant features of my new design are shown in solid lines.

I claim:

The ornamental design for a table lamp, substantially as shown and described.
